UNITED STATES PATENT OFFICE

2,516,469

OIL HEATING STOVE HAVING J-SHAPED BAFFLES THEREIN

Alfred Kozak, Chicago, Ill.

Application May 28, 1947, Serial No. 751,079

6 Claims. (Cl. 126—93)

1

The present invention relates to new and useful improvements in stoves and more particularly to oil heating stoves designed to heat a room or other area by direct radiation.

An important object of the present invention is to provide an oil heating stove constructed to use a low grade heating oil and providing a heat radiating casing having an arrangement of baffles therein by means of which the products of combustion from the burner travel in a tortuous path to more effectively heat the casing before the heated gases or products of combustion are permitted to leave the casing to a chimney or other outlet.

A further object of the invention is to provide a baffle arrangement for mounting as a unitary structure in a heat radiating casing of an oil stove.

A further object is to provide a casing for a stove of this character having a door in one side thereof to provide access to the baffles for efficiently cleaning the latter.

A still further object is to provide an apparatus of this character which is simple and practical in construction, which is neat and attractive in appearance, efficient and reliable in operation and otherwise well adapted for the purposes for which the same is intended.

Other objects and advantages reside in the details of construction and operation as more fully hereinafter described, and claimed, reference being had to the accompanying drawings forming part hereof, wherein like numerals refer to like parts throughout, and in which:

Figure 1 is a perspective view;

Figure 2 is a transverse sectional view taken substantially on the line 2—2 of Figure 1;

Figure 3 is a sectional view taken on the line 3—3 of Figure 2; and,

Figure 4 is a fragmentary elevational view with parts broken away and shown in section and illustrating a modified form of the invention.

Referring now to the drawings in detail, and first with respect to the form of the invention illustrated in Figures 1 to 3 inclusive, the numeral 5 designates a sheet metal casing of substantially rectangular shape which is open at its bottom and having its lower edges formed with inwardly extending flanges 6 to support the casing on a floor of a room. The lower rear wall 7 of the casing is formed with an air inlet opening 8.

2

An oil burner 9 of conventional construction is placed centrally in the lower portion of the casing and upon which a fuel supply pipe 10 extends through the opening 8 to a suitable source of fuel supply. An outlet pipe 11 extends from the rear wall 7 adjacent its upper portion to a chimney or the like.

Each of the side walls 12 of the casing is provided with a relatively large hinged door 13 secured in a closed position by a conventional catch 14, the door providing access to the interior of the casing through either side thereof.

An open rectangular frame member 15 preferably constructed of angle iron members is snugly fitted in the casing 5 and includes a sheet metal top 16 and a sheet metal bottom 17 having a central opening 18 communicating with the top of the burner 9, the bottom 17 resting on the top of the burner to support the frame 15 above the bottom of the casing as shown in Figure 3 of the drawings.

A plurality of lower J-shaped sheet metal baffle members 19 have their lower ends welded or otherwise suitably secured to each other as shown at 20 and with the vertical portions 21 of said baffles arranged in spaced parallel relation with respect to each other.

A lower baffle plate 22 of sheet metal construction and of substantially U-shaped has one end 23 secured at the bottom of the outlet for the casing 5 and extends downwardly therefrom to rest on the bottom 17 as shown at 24 to prevent direct passage of the products of combustion from the burner 9 to the outlet. The lower portion of the baffle 22 is curved upwardly from the point 24 above the burner 9 to deflect the products of combustion from the burner 9 toward the front of the casing and the other end 25 of the baffle 22 is supported in an upstanding position in spaced relation from the front wall of the casing.

The group of baffle members 19 is secured at its front edge to the front end 25 of the baffle member 22 as shown at 26.

The vertical portions 21 of the group of baffles 19 are arranged in spaced parallel relation with respect to the upper end 25 of the baffle 22, the upper ends of said vertical portions 21 and 25 terminate below the top 16 of the frame 15.

An upper group of J-shaped baffles 27 are secured in an inverted position in the frame 15 by welding the curved end of one of the baffles

to the front portion of the frame as shown at 28 and with the curved upper portions 29 of said group of baffles 27 spaced above the upper ends of the lower group of baffles 19 as well as above the upper end 25 of the baffle 22. The vertical portion 30 of the group of baffles 27 are spaced from the vertical portions 21 of the baffles 19 as well as from the vertical portion 25 of the baffle 22 whereby to provide a tortuous passage for the products of combustion from the burner 9 to cause the same to travel upwardly and downwardly between the upper and lower groups of baffles as shown by the arrows in Figure 3 of the drawings before leaving the casing 5 to enter the discharge pipe 11.

The upper portion of the outlet at the rear of the casing 5 is connected to the upper portion of the upper group of baffles 27 by a curved baffle 31 to prevent pocketing of the products of combustion or heated gases at the upper rear portion of the casing.

The several sheet metal baffles extend transversely of the casing 5 from side to side thereof so that the edge portion of the baffles are positioned adjacent the door 13 at the opposite side of the casing to thus facilitate the cleaning of soot from the baffles upon opening the door.

In Figure 4 of the drawings I have illustrated a modified form of the invention which comprises a tubular coil 32 positioned in the casing 33 and formed at its lower end with an enlarged throat 34 connected to the top of the burner (not shown) and an outlet throat 35 which is connected to the pipe 36 extending from the back of the casing.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A heating stove comprising a sheet metal casing having a burner in its lower portion and an outlet for products of combustion from the burner in its upper portion, and a series of baffles in the casing between the burner and the outlet, said baffles including upper and lower groups of substantially J-shaped sheet metal members having their vertical portions arranged in spaced parallel relation from each other, said upper group of baffles being inverted and the curved ends of the baffles of each group abutting an adjacent correspondingly arranged baffle, and the straight ends of one group of baffles being spaced from and also centered in the curved ends of the opposite group of baffles to form a tortuous passage in the casing.

2. A heating stove comprising a sheet metal casing having a burner in its lower portion and an outlet for products of combustion from the burner in its upper portion, and a series of baffles in the casing between the burner and the outlet, said baffles including groups of opposed substantially J-shaped sheet metal baffles having their straight end portions arranged in spaced parallel relation with respect to each other the curved ends of the baffles of each group abutting an adjacent correspondingly arranged baffle, and

the straight ends of one group of baffles being spaced from and also centered in the curved ends of the opposite group of baffles to form a tortuous passage in the casing.

3. A heating stove comprising a sheet metal casing having a burner in its lower portion and an outlet for products of combustion from the burner in its upper portion, and a series of baffles in the casing between the burner and the outlet, said baffles including groups of opposed substantially J-shaped sheet metal baffles having their straight end portions arranged in spaced parallel relation with respect to each other, the curved ends of the baffles of each group abutting an adjacent correspondingly arranged baffle, and the straight ends of one group of baffles being spaced from and also centered in the curved ends of the opposite group of baffles to form a tortuous passage in the casing, and doors in the opposite sides of the casing at the edge portions of the baffles of an area to include both groups of baffles.

4. A heating stove comprising a sheet metal casing having a burner in its lower portion and an outlet for products of combustion from the burner in its upper portion, an open frame conforming to the casing and fitting therein, and sheet metal baffles supported in the frame and including upper and lower groups of substantially J-shaped baffle members arranged with their straight ends in spaced parallel relation with respect to each other and with the curved ends of each group of baffles closed against an adjacent baffle of its group and said curved portions at their inner surfaces being opposed to and spaced from the straight ends of the opposed baffles with the straight end of each baffle centered in the curved end of an opposing baffle to form a tortuous passage in the casing between the burner and the outlet, and a deflector directing products of combustion from the burner to one end of said passage.

5. A heating stove comprising a sheet metal casing having a burner in its lower portion and an outlet for products of combustion from the burner in its upper portion, an open frame conforming to the casing and fitting therein, and sheet metal baffles supported in the frame and including upper and lower groups of substantially J-shaped baffle members arranged with their straight ends in spaced parallel relation with respect to each other and with the curved ends of each group of baffles closed against an adjacent baffle of its group and said curved portions at their inner surfaces being opposed to and spaced from the straight ends of the opposed baffles with the straight end of each baffle centered in the curved end of an opposing baffle to form a tortuous passage in the casing between the burner and the outlet, and a deflector directing products of combustion from the burner to one end of said passage, said baffles having their edge portions positioned against opposite side walls of the casing, and doors in said walls of an area to include both groups of baffles.

6. A heating stove comprising a sheet metal casing having a burner in its lower portion and an outlet for products of combustion from the burner in another portion, and a baffle structure in the casing forming a tortuous passage leading from the burner to said outlet, said baffle structure comprising opposed groups of substantially hook-shaped sheet metal plates, the bill portions of the plates of each group contacting each other and the shank portions of the plates of one group being centered in and spaced from the bill por-

tion of an opposed plate to reverse the direction of flow of products of combustion between the plates.
